COMBINED TOY TOOLBOX AND WORK BENCH

Duane E. Spengler, West Falls, N.Y., assignor to Fisher-
Price Toys, Inc., East Aurora, N.Y., a corporation of
New York

Filed Mar. 6, 1969, Ser. No. 16,095

Term of patent 14 years

Int. Cl. D21—02

U.S. Cl. D34—15

FIG. 2

FIG. 3

FIG. 1 is a front perspective view of a combined tool box and workbench showing my new design;

FIG. 2 is a rear perspective view thereof; and

FIG. 3 is a front perspective view on a reduced scale showing the cover of the toolbox open and exposing the workbench surface.

I claim:

The ornamental design for a combined toy toolbox and work bench, substantially as shown and described.
